UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,537, dated December 31, 1889.

Application filed December 6, 1889. Serial No. 332,827. Term of patent 3½ years.

To all whom it may concern.

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is illustrated as having a first and second story and an attic story, together with a rear extension. At one corner there is illustrated a tower. At the front of the residence there is shown at one corner a rectangularly-shaped bay A upon the first story. At one side of the bay A is a porch B, to which steps a lead. At one side of the residence is an L C, which L has

substantially flat exteriors throughout both 25 the first and second stories. The L C is surmounted by a gable roof D.

A gable roof E surmounts the main portion of the residence, extending from the front to the back. The rear extension F has substantially flush sides and is surmounted by a gable roof G.

A tower H rises from the second story at one corner of the residence, and is surmounted by an ogee-shaped roof I. Pillars h at the 35 porch B are represented as supporting the tower H. Above the pillars h is a molding i, and between the molding i, extending between it and the base of the tower H, are consoles j.

What I claim is—

The design for the exterior of a residence, substantially as herein shown and described.

WILLIAM K. BENEDICT.
